Primary Examiner — George D. Kirschbaum*Assistant Examiner* — Denis Houyoux*(74) Attorney, Agent, or Firm* — Ruggiero, McAllister & McMahon, LLC(57) **CLAIM**

The ornamental design for an outdoor power post cover, as shown and described.

DESCRIPTION

FIG. 1 is a perspective view of an outdoor power post cover according to the present design;

FIG. 2 is a front view of the outdoor power post cover of FIG. 1;

FIG. 3 is a rear view of the outdoor power post cover of FIG. 1;

FIG. 4 is a left side view of the outdoor power post cover of FIG. 1;

FIG. 5 is a right side view of the outdoor power post cover of FIG. 1;

FIG. 6 is a top view of the outdoor power post cover of FIG. 1; and,

FIG. 7 is a bottom view of the outdoor power post cover of FIG. 1.

The broken line showing of FIGS. 1-7 is for the purpose of illustrating environmental structure and forms no part of the claimed design.

1 Claim, 6 Drawing Sheets(56)
